UNITED STATES PATENT OFFICE

ALBERT BACHRACH, OF DECATUR, ILLINOIS

FURNITURE

Application filed August 1, 1928. Serial No. 296,658.

This invention broadly relates to improvements in furniture, and more particularly to a method and means for vermin prevention and eradication from upholstered furniture.

5 The object of the invention is to provide improved furniture that will be sanitary, free from vermin and disease spreading micro-organisms.

10 Another object is to provide improved means of the kind described for efficiently disinfecting upholstered furniture, for the prevention and destruction of moths, insects, etc., thus contributing to the comfort of the user and the preservation of the upholstery.

15 Other objects will appear hereinafter.

In the drawings Figure 1 is a perspective view of a sofa wherein my invention is embodied.

20 Figure 2 is a perspective view of an upholstered seat showing my invention in a slightly modified form.

Figure 3 is an elevational view, partly in section, of an upholstered chair with my invention applied thereto.

25 Figure 4 is a perspective view of my device shown as it appears detached from an article of furniture.

Figure 5 is a fragmentary enlarged sectional detail view of a valve employed by me 30 in connection with my invention.

With more particular reference to the drawings wherein similar characters of reference indicate corresponding parts in the several views, A designates a sofa of conventional type having a seat 9, curving arms 10 and a back 11. In the rear of the arms, back and seat, valves 12 are provided which connect with pipes 13 having perforations 14, the pipes extending through the arms, back and seat, as shown in Figure 1.

40 In Figure 2 the pipe 13 is shown extending in helical form, the valve 12 projecting slightly beyond the outer edge of any convenient portion of the seat member 9 shown.

45 Figure 3 shows my invention applied to a chair, the back thereof being shown in section with the pipe 13 extending upwardly therefrom from the valve 12.

50 In Figure 4 a system of intercommunicating pipes 13 is shown to which access is had

by the valve 12. The relative position of this system of disinfecting pipes to an arm chair is indicated by the dotted lines which roughly indicate the said chair.

The valve 12 through which any suitable 55 disinfecting medium, such as sulphur dioxide, hydrocyanic acid gas, formaldehyde, etc., is injected into the pipes and thence through the perforations into the upholstery of the furniture, is shown in Figure 5. 60 This valve also serves to prevent the return of the liquid or gas injected to the outer air by reason of back pressure from within, thus permitting the use of the powerful disinfectants indicated. Figure 5 designates 65 the valve as a whole, which is provided with a circumferential flange 15 and an inner bore 16 having an inner tapering portion 17, which is again widened to provide a seat 18 for a ball 20 closing a widened chamber 70 19 into which the bore 16 communicates. By inspection of this figure it will be seen that the ball 20 is resiliently maintained in the seat 18 by means of a spring 21 which is received in a recess 22 formed in a plug 23 75 having longitudinal channels 24, which latter serve as a means of communication between the channels of the pipe 13 and the widened chamber 19. The plug 23, which is threaded, also serves to connect the valve 80 12 with the pipe 13, as clearly shown in Figure 5.

The mode of operation and use of my device has been in part indicated from the foregoing disclosure, but may be more fully 85 apparent by the following brief explanation:

Assuming the device to be installed in the articles of furniture illustrated in Figures 1 to 4 inclusive, it will be desirable at periodic intervals of time, which will differ at different seasons of the year and in different climates, to connect the valve 12 with any suitable means for injecting disinfecting gases of the type indicated above or air 90 laden with insect destroying powder. In practice I have found it efficient and convenient to connect the valve 12 to cylinders 95 of compressed gases of the types indicated. By opening up the valve of the cylinders 100

to a suitable degree, a rush of the gaseous disinfectant through the valve 12 and through the communicating pipes, and thence through the perforations 14 into the upholstery, will occur. If desired, the furniture in connection with this process may be simultaneously sweetened by the intermingling of some gas of agreeable odor with the disinfecting gas, or this may be done subsequent to disinfection. I have found the use of gases and power laden air preferable to liquids, although these of the more volatile type may be employed.

The invention is especially valuable in such climates and localities where vermin prove an ever prevalent pest, this being particularly true during the summer months and in the tropical climates. I am aware of upholstered furniture wherein has been incorporated means which are brought into play when the furniture is in use, the principle involved being that of the bellows. The chief disadvantage to this method is that the source of supply is quickly exhausted if the articles of furniture are used frequently. It is also impractical to employ such powerful means of vermin eradication, as has been herein indicated feasible, for obvious considerations.

30 It will be obvious that the invention is susceptible of some modification and change, hence I do not confine myself literally to the exact details as set forth, but desire to avail myself of such modifications and variations as fairly fall within the scope of the appended claims.

What I claim as new and desire to secure by Letters Patent is:

An article of furniture of the character described, comprising a framework having upholstered portions, and a plurality of rigid interconnected tubular members disposed within the upholstering of said upholstered portions, said tubular members provided with a plurality of perforations and having a common inlet and check valve connection, whereby a gaseous disinfectant may be administered under pressure and distributed through said upholstering.

50 In testimony whereof I have signed my name to this specification.

ALBERT BACHRACH.
